DESIGN FOR A DOLL'S STALL SHOWER

Marshall A. Marshall, Buffalo, N. Y.

Application October 3, 1946, Serial No. 133,719

Term of patent 7 years

(Cl. D34—15)

To all whom it may concern:

Be it known that I, Marshall A. Marshall, a citizen of the United States, residing at Buffalo, in the county of Erie and State of New York, have invented a new, original, and ornamental Design for a Doll's Stall Shower, of which the following is a specification, reference being had to the accompanying drawing, forming a part thereof.

In the drawing showing my new design of a doll's stall shower:

Fig. 1 is a perspective view;

Fig. 2 is a front elevational view with the door in open position; and

Fig. 3 is a side elevational view.

I claim:

The ornamental design for a doll's stall shower, as shown.

MARSHALL A. MARSHALL.
